UNITED STATES PATENT OFFICE.

IVAR LUNDGAARD, OF HARTFORD, CONNECTICUT, ASSIGNOR TO THE AUTOMATIC REFRIGERATING COMPANY, OF HARTFORD, CONNECTICUT, A CORPORATION OF NEW JERSEY.

AIR-REFRIGERATING MACHINE.

Application filed March 30, 1922. Serial No. 548,518.

To all whom it may concern:

Be it known that I, IVAR LUNDGAARD, a citizen of the United States, and a resident of Hartford, county of Hartford, State of Connecticut, have invented certain new and useful Improvements in Air-Refrigerating Machines, of which the following is a specification.

My invention relates primarily to air refrigerating machines of the type described in my Patent No. 1,240,862. In such machines, air is used as the mediating fluid and is alternately compressed and expanded, heat being removed from the compressed air by a cooling fluid and extracted from a fluid to be refrigerated by the mediating air in the expanded condition. These operations are carried out in a cylinder having a compression piston and a shifter piston suitably operated to compress and expand the air in the desired cycle while at the same time passing it through the heat exchangers and regenerator.

In order that the machine may give good results, it is necessary that the pistons and cylinder be properly lubricated without permitting oil to be carried by the swift air currents into the air passages or into the cold end where it would tend to congeal, due to the extremely low temperature there present. In any cylinder using a trunk piston, there is a tendency to push oil up the cylinder wall along one side of the piston and down along the other side of the piston. This is due to the variation in side pressure between the piston and cylinder wall resulting from the angularity of the connecting rod or analogous part.

The thickness of a film of oil existing between rubbing surfaces and the movement of such a film are functions of the liberality of the oil supply and the pressures between the surfaces and the relative speed of the surfaces. In the event of oscillating motion under varying pressures of one surface against another, oil will in general be carried in the direction of the movement taking place under the greatest average pressure. Thus, considering a trunk piston reciprocating in a vertical cylinder and receiving lubrication by splash action from an actuating chamber below, that side of the piston which is under the greatest pressure

during the up-stroke of the piston will carry oil upwards. The result of this is to cause accumulation of oil on the top of the piston. The object of the present invention is to provide means for preventing oil from getting into the cold end or on top of the piston, while at the same time insuring proper lubrication.

To attain this object, I provide first, a chamber, in which oil pushed up by the piston may accumulate, second, a passage through which the oil may be carried from the chamber to some point of the circumference of the piston other than that at which the oil has been pushed up and where it may pass down. The chamber and passage are so located and formed that they are not subject to detrimental effects of the air currents in the cylinder. This chamber may be either in the piston or the cylinder and in either case is located at the upper limit of contact surface of the member in which it is located, an extension of the piston running in close proximity but not touching the wall of the cylinder performing the function of protecting the oil in the chamber from the air passing into and out of the cylinder.

In order that my invention may be readily understood, it is described in connection with the accompanying drawings, in which

Figure 1 is a vertical section through the two cylinders of my air refrigerating machine.

Figure 2 is an enlarged section of the compression piston of the machine of Figure 1, showing the adjacent parts of the cylinder.

Figure 3 is a view showing a modification of the piston wherein the oil groove is in the piston.

Referring more particularly to the drawings, the compression piston 1, Figure 1, is shown in its lowest position and the compression piston 2 is shown in its highest position. The shifter piston 3 is at its highest position. Shifter piston 4 has reached a position from which it follows compression piston 2 downward for a certain distance. The compression pistons are driven through links 5, walking-beam 6, connecting rod 8, and crank-pin 9, from shaft 10. The shifter piston 3 is driven by rod 11 which

passes through a bushing 12 in piston 1 and is guided at its lower end in guide 13. This rod is actuated by cam 14 through roller 15, lever 16, and a link 26 connecting the end of lever 16 with the spring seat 17, which is attached to the rod 11. The spring 18 serves to hold the cam roller 15 on the cam 14 and drives the piston 3 in one direction. Shifter piston 4 operates in a similar manner.

The rod 11 and the piston 1 are lubricated by splash lubrication supplied by the connecting rod 8 which dips into the oil in the crank-case at each revolution. The oil level is indicated by the dotted line 19 and may be varied to supply more or less oil to the moving parts.

A groove 20 is formed in the cylinder wall 21 at a point slightly below the top of the piston 1 in its lowest position. Groove 20 extends completely around the cylinder wall and provides a path for oil that is pushed up by the piston to flow around the piston to a point where it will be carried down again to the crank case. If, for example, we assume that the arrow 22 (Figure 2) represents the direction of side thrust on the up-stroke and arrow 23 the direction of side thrust on the down-stroke, oil will be carried up on the left side of the piston and down on the right side. The exact points where oil will be carried up or down depend on the driving mechanism of the piston and the way in which the gas pressure 35 above and below the piston varies. The actual difference of fluid pressure between the spaces above and below the piston has little effect on the amount of oil pushed up or down by the piston except as it determines the side pressure on the piston. Further, in certain types of engines, the side pressure may be always toward one side, with variation of intensity only. In all these cases, the groove 20 serves to distribute the oil pushed up, to some point where it will pass down again.

It is to be noted that recess 27 formed at the upper end of the bushing 12 in the piston 1, operates on the same principle as groove 20 and serves to prevent oil from being carried to the top of the piston by the action of shifter rod 11 sliding in piston bushing 12.

Using the construction shown in Figure 1, I have found that, after many hours running, no oil is to be found on top of the piston, or in the air passages.

In Figure 3, a modified form of piston 1 is shown. The annular oil groove 20 is turned in the outside wall of the piston toward its upper end and the portion 25 of the piston above the groove 20 has clearance between it and the cylinder wall 21.

The amount of oil supplied to the piston 65 may be varied by the use of a thin sleeve

24 (Figure 2) attached to the lower end of the piston 1. The function of this sleeve is to prevent some of the oil splashed from striking the cylinder and piston. By varying the length of the sleeve, this effect can be varied.

As shown in Figures 2 and 3, the pistons are at their lowest positions. Their highest positions are indicated by dotted lines.

It is to be noted that the location of the chamber for receiving the surplus oil is important in that it must always be at the upper limit of the contacting surfaces and yet not high enough to overflow the top of the piston or into ports or clearance spaces where it might be affected by the air currents. There being no contacting surfaces above the oil chamber there will be no pumping up of oil above the chamber and there being a clearance between the upper part of the piston and the cylinder wall this part of the piston will not pump oil so that the chamber is as high as the oil can get. It follows, therefore that the non-contacting upper extension of the piston will act as a shield to prevent the air currents in the cylinder from sweeping up the oil and carrying it where it is not wanted.

I am aware that it is not new to provide oil grooves either in the piston or in the cylinder for effecting a distribution of the oil but there have always been contacting surfaces above even the top oil groove so that pumping of oil into the top of the piston or into ports or clearance spaces has not been avoided.

Although my invention is described in connection with air-refrigerating machines, it is useful in connection with other types of reciprocating engines, especially those having vertical cylinders and using a gaseous fluid. Other modifications are possible and I do not limit myself to the embodiment shown herein.

I claim:—

1. Cylinder and piston construction comprising a cylinder, a piston reciprocable therein, an oil passage in one of said members extending from one portion of the piston circumference to another, said cylinder and piston having a construction to at all times restrict communication with said passage from the space above the piston while avoiding contact between the cylinder and piston above said passage.

2. Cylinder and piston construction comprising a cylinder, a piston reciprocable in said cylinder, means for supplying fluid lubricant for said piston, an oil chamber at the upper limit of the contacting surface of said piston and cylinder, said oil chamber leading from one side of the cylinder to the opposite side, the piston and cylinder coextending above the oil chamber with clearance to prevent contact and thus form

110

115

A zone above the oil chamber that is non-fabricated and protected from freely moving gas.

3. Cylinder and piston construction comprising a cylinder, a piston reciprocable in said cylinder, a circumferential oil chamber in the piston at the upper limit of its contacting surface, the piston above the oil

chamber having a cylindrical extension, said extension being of less diameter than the cylinder sufficient to prevent contact and the outlet for oil from the oil chamber limited to the space between the contacting surfaces of the cylinder and piston.

IVAR LUNDGAARD.
